Attorneys.

UNITED STATES PATENT OFFICE

WARREN H. HUNGERFORD, OF CHICAGO, ILLINOIS

WIRE BAKING PAN

Application filed July 3, 1930. Serial No. 465,584.

This invention relates to a pan, vessel, container or support for use in connection with baking. In the form illustrated herewith it comprises a relatively flat member upon which articles to be baked may be held and supported during the baking operation.

It has for one object to provide in connection with such a device a construction which permits of ready and complete cleaning. Another object is to provide a device in which the entire surface may be used to carry goods for baking and in which misshapement and discoloration of the goods are impossible.

Other objects will appear from time to time in the specification and claims.

My invention is illustrated more or less diagrammatically in the accompanying drawing, wherein—

Figure 1 is a plan view of one form of my invention;

Figure 2 is a transverse vertical cross section taken on an enlarged scale at line 2—2 of Figure 1;

Figure 3 is a fragmentary cross section, generally similar to Figure 2, of a modified form of my invention;

Figure 4 is a fragmentary cross section, generally similar to Figure 2, of a further modified form of my invention;

Figure 5 is a fragmentary cross section, generally similar to Figure 2, of a further modified form of my invention;

Figure 6 is a fragmentary cross section, generally similar to Figure 2, of a further modified form of my invention;

Figure 7 is a fragmentary cross section, generally similar to Figure 2, of a further modified form of my invention;

Figure 8 is a fragmentary cross section, generally similar to Figure 2, of a further modified form of my invention;

Figure 9 is a fragmentary cross section, generally similar to Figure 2, of a further modified form of my invention.

Like parts are designated by like characters throughout the specification and drawings.

50 The supporting surface is formed of a

screen or grid A. This screen is supported by a frame which is preferably metallic and which serves to provide necessary rigidity to hold the screen taut and to permit handling and moving of the device as a whole. 55 In the form illustrated in Figures 1 and 2, the frame is formed of a member B provided with an upstanding edge or flange B¹ and a second flange B² which is bent backward upon itself so that the major portion 60 of it is parallel to the member B. The edge A¹ of the screen A is gripped and held taut between the portions B and B². By means of this construction the effective screen surface extends from edge to edge of the entire device. The screen is only in contact with the frame at its extreme outer edge and a considerable gap or space is provided between the upper surface of the portion B and the lower surface of the screen. Thus the device 65 may be readily cleaned as a brush or other instrument may be inserted between the screen and the frame. In the form illustrated in Figure 3, the members B, B¹ and B² are the same as those shown and described in connection with Figure 2. As an added strengthening and gripping member, however, the member B² is extended by the provision of an upturned edge B³. Thus in 70 the form shown in Figure 3 the edge of the screen is gripped between the members B and B² and between the two upturned portions B¹ and B³. This forms a somewhat stronger device than that illustrated in the preceding figure and one in which the screen 75 is gripped by the frame over a greater area. 80

In Figure 4 the frame is formed of a member C having a flange or lip C¹ outwardly bent with respect to the member C. Thus the members C and C¹ lie substantially 90 parallel throughout a portion of their width and the member A¹ is gripped between them. The member C is provided with an upwardly extending curved lip portion C² about which the edge of the screen A is 95 wrapped.

In Figure 5 the frame consists of upper and lower portions D, D¹, respectively, which are generally parallel to each other and between which the edge A¹ of the screen A is 100

gripped. Resting upon the upper surface of the member D and between it and the screen A is a rod or other spacing member E which serves as a means for supporting the screen A and for holding it out of contact with the member D except at the edge of the latter.

In Figure 6 the frame is formed of a rod-like member F about which the edge 10 A¹ of the screen A is wrapped. Surrounding the rod F, being preferably generally concentric with it and serving with it to grip the edge A¹ of the screen is a member G. This member is preferably so proportioned as to be in contact only with the edge A¹ of the screen A and to be out of contact with the under surface of the main portion of the screen A.

In Figure 7 the frame is formed of a 20 member H which is preferably inclined with respect to the plane of the screen A. The member H is provided with an inwardly or downwardly bent lip or flange H¹ which may lie parallel with it, and is joined to 25 its upper edge. The edge A¹ of the screen is gripped between the portions H and H¹. The member H is provided with an outwardly extending flange or lip H² which 30 serves as an additional stiffening and strengthening member and in the form here shown is generally parallel with the plane of the screen A.

The form shown in Figure 8 is generally the same as that shown in Figure 7, 35 except that the flange or lip H² is omitted.

In the form shown in Figure 9, the frame is formed of a downwardly and inwardly inclined member I to the lower edge of which is attached an upwardly and outwardly inclined member I¹. Between the two the edge A¹ of the screen A is engaged and gripped.

It will be realized that while I have herein shown and described a practical operative device, nevertheless many changes might be made in the size, shape, number and disposition of parts without departing from the spirit of my invention, and I wish, therefore, that my showing be taken as in 50 a sense diagrammatic. Particularly, the details of construction might be almost infinitely varied. While in most of the forms shown the members of which the frame is built up are unitary with the various flanges 55 and lips formed as a part of the frame itself, this obviously might be varied and any form, such as that shown in Figure 2 or any other figure, might be formed of separate parts attached, and thus in the form 60 shown in Figure 2, the member B² might be separate from the member B and the two might be bolted, riveted or otherwise fastened together so as to grip the screen and to serve the other purposes and accomplish 65 the other objects of the frame.

Where in the specification and claims I use the expression "wire mesh", I wish this expression to be taken as including any supporting member which has a relatively large portion of its surface open. For the sake of convenience the expression "wire mesh" has been used but it is to be taken as including a cloth which might be made of strips rather than wires or bars or even a sheet of material having a large part of its surface cut away. This might be a sheet of metal with many perforations of any shape whatever, so as to provide a relatively large, open, cut-away or unobstructed proportion of the total area.

It will be understood that the device of my invention is not limited to use in the baking industry. A pan of the sort described might be used in many other industries, such, for example, as the manufacture of breakfast foods, macaroni, candy and many others.

The use and operation of my invention are as follows:

In any of the forms illustrated, my invention is made as shown and is used to support goods for baking. Heretofore, where pans have been used and particularly where pans formed of screening have been used, it has been thought necessary to use a relatively wide frame, in contact with the screen. The heating effect upon goods resting upon the metallic frame is different from that upon goods resting upon the screen. Thus a cooky which rests upon the screen will have a different color from one which rests upon the frame at the edge of the pan and for many purposes such cookies of different colors, or so-called "discolored" cookies, must be rejected. Also, when sagging of the screen portions develops, this sagging occurs from the edge of the frame member and if the frame is relatively wide, a cooky or other article to be baked might rest partly on the screen and partly on the frame member, or partially on a portion of the screen which is in direct contact with the frame member. It is, therefore, supported by it and does not sag. When a cooky thus rests upon the supported part 110 of the screen, it will be an uneven shape and so must be rejected.

In my invention, since the screen surface extends to the very edge of the pan and since it is throughout practically its entire 120 working area out of contact with the frame, everything which is positioned upon the frame rests upon the screen surface and upon it alone and rests upon the screen at a point at which it is out of contact with the frame. Thus all of the goods carried by the screen of my invention are subject to the same conditions of heat and discoloration is impossible. Any sagging which may occur in the screen will occur throughout its en- 130

tire area and so any article upon the total working surface of the screen will have the same bottom shape as any other article and so distortion does not occur. Thus my invention avoids distortion and avoids discoloration. Since the screen in all forms is separated from the frame which carries it throughout its entire working area, it is possible to clean the entire screen and the frame readily because a brush or other tool may be run under the screen between it and the frame.

In use, the pans of this invention are used to support goods which are to be baked. The goods are positioned on the upper surface of the screen and the pan is put in the oven and the necessary baking or other heating or cooking operation is carried out. When this operation is finished, the pans are removed and the baked or cooked goods are removed from the pans.

I claim:

1. In combination in a baking pan, a wire mesh material portion constituting a goods carrying part and forming substantially the entire upper surface of said pan, a frame therefor, the frame including two oppositely placed co-operating members adapted to engage the edge of the wire mesh, one of said members provided with a spacer adapted to contact the wire mesh portion, and to hold that portion of the same which constitutes the goods carrying part out of contact with the surface of the engaging member, the other engaging member extending laterally beyond the edge of the wire mesh.

2. As a new article of manufacture, a baking pan including a circumferential frame member having an upper flange and a lower flange, the upper flange carrying an upwardly extending lip, the lower flange having a continuation extending outwardly beyond the edge of the upper, and lying in the plane of the lower flange, and a wire mesh baking surface member forming substantially the entire upper surface of said pan the edge of which penetrates between the two flanges, the body of which rests upon the upward extension from the upper flange and is bent downwardly about the edge of the upper flange, said continuation constituting a guard member.

3. As a new article of manufacture, a baking pan which includes a circumferential frame member having an upper element and a lower element, said upper element provided with an upwardly extending lip, the lower element extending outwardly beyond the edge of the upper, and a wire mesh baking surface member forming substantially the entire upper surface of said pan resting upon said upwardly extending lip and out of contact with the upper surface of

the upper frame element, the edge of said wire mesh penetrating between the two elements but being contained within the periphery of the lower element, the upper surface of said wire mesh baking member being free throughout the effective upper area of the mesh.

4. As a new article of manufacture, a baking pan, a wire mesh member forming a baking surface forming substantially the entire upper surface of said pan, a frame element about the edge of said mesh, the wire mesh baking surface extending over said frame to the effective edge of the pan, that portion of the wire mesh which forms the baking surface being free throughout the area of the pan, and a laterally extending guard for the edge of said wire mesh baking surface member, the frame element including a portion extending upwardly from its surface and serving as the contacting portion for the under surface of the wire mesh.

5. As a new article of manufacture, a baking pan, a wire mesh member forming a baking surface forming substantially the entire upper surface of said pan, a frame element about the edge of said mesh, said frame including an upwardly extending wire mesh contacting part, that portion of the wire mesh member forming the baking surface extending over said frame to the effective edge of the pan and contacting only said upwardly extending part, the upper surface of said wire mesh baking surface being free throughout the area of the pan, and a laterally extending guard for the edge of said wire mesh baking surface member, said guard member forming part of the said frame element.

6. In a baking pan, a frame, a sheet of mesh material forming the baking surface of said pan, said frame including an upstanding supporting member adjacent the outer edge of the frame, upstanding to a level above that of the inner edge of the frame, the mesh contacting the upstanding supporting member and overlying and being spaced above and out of contact with the inner portion of the frame.

7. In a baking pan, a frame, a sheet of mesh material forming the baking surface of said pan, said frame including an upstanding supporting member adjacent the outer edge of the frame, upstanding to a level above that of the inner edge of the frame, the mesh contacting the upstanding supporting member and overlying and being spaced above and out of contact with the inner portion of the frame, the mesh being bent downwardly about the exterior of said upstanding supporting member and its edge being gripped within a lower portion of the frame.

8. In a baking pan, a frame, a sheet of

mesh material forming the baking surface of said pan, said frame including an upstanding supporting member adjacent the outer edge of the frame, upstanding to a level above that of the inner edge of the frame, the mesh contacting the upstanding supporting member and overlying and being spaced above and out of contact with the inner portion of the frame, the mesh being bent downwardly about the exterior of said upstanding supporting member and its edge being gripped within a lower portion of the frame, said edge portion of the mesh extending inwardly within the periphery of the pan defined by the zone of contact between the mesh and the upstanding supporting member.

9. In a baking pan, a frame, a sheet of mesh material forming the baking surface of said pan, said frame including an upstanding supporting member adjacent the outer edge of the frame, upstanding to a level above that of the inner edge of the frame, the mesh contacting the upstanding supporting member and overlying and being spaced above and out of contact with the inner portion of the frame, a portion of said frame extending laterally outwardly beyond the edge of the baking surface defined by the zone of contact between the mesh and the upstanding supporting member.

10. In a baking pan, a frame, a sheet of mesh material forming the baking surface of said pan, said frame including an upstanding supporting member adjacent the outer edge of the frame, upstanding to a level above that of the inner edge of the frame, the mesh contacting the upstanding supporting member and overlying and being spaced above and out of contact with the inner portion of the frame, said upstanding supporting member being mounted upon but separable from the rest of the frame.

11. In a baking pan, a unitary frame formed of sheet metal, said frame including an upstanding supporting flange adjacent the outer edge of the frame, extending to a level above that of the inner portion of the frame, the mesh contacting the upstanding supporting flange and overlying and being spaced above and out of contact with the portion of the frame situated inwardly of said flange, the edge of the mesh being gripped between opposed portions of the frame at a level below the level of the engagement of the mesh with the flange.

12. In a baking pan, a frame, a sheet of mesh material forming the baking surface of the pan, said frame including an outer edge portion upstanding to a level above that of the inner edge of the frame, the mesh contacting the upstanding outer edge portion and overlying and being spaced above

and out of contact with the inner portion of the frame.

Signed at Chicago county of Cook and State of Illinois, this 12th day of June 1930.
